UNDERFRAME AND ADJOINING SIDE WALL
STRUCTURE OF RAILWAY CARS AND SIM-
ILAR VEHICLESAlbert G. Dean, Narberth, Pa., assignor to The
Budd Company, Philadelphia, Pa., a corpora-
tion of Pennsylvania

Application October 24, 1947, Serial No. 782,002

10 Claims. (Cl. 105—397)

1

The invention relates to railway cars and to the bodies of similar vehicles and, more particularly, to the underframe and adjoining side wall construction as well as to the connection between side wall and underframe. More specifically, the invention relates to a railway car or similar vehicle body composed of separately pre-assembled underframe and side wall units.

Among the objects of the invention is a structure of the indicated type which is of simple design, the parts of which are easily and simply made and assembled, which is of light weight, and which affords ample strength.

With the aforesaid objects in view, one feature of the invention consists in U-section side rails or sills for the underframe telescopingly fitting over the ends of vertically reinforced cross members and connected with an inner web of the sill structure and the posts of each side wall, said side wall sill structures extending downwardly below the underframe sills and enclosing the vertical posts of the side walls on the inside, on the outside, and at the bottom.

The invention consists, furthermore, in the connection between underframe sill and side wall with the bolsters supporting the vehicle body on the wheeled trucks.

Furthermore, the invention consists in the formation of additional cross braces arranged between the bolsters and fitting between adjoining webs of the floor panel.

A still further feature of the invention resides in a box sectional step below a door opening affording a strengthening element for the side wall where the latter is weakened by the door opening.

The above and other features, advantages and objects of the invention will be more easily understood from the illustration of one embodiment in the attached drawing and from the following detailed description thereof.

In the drawing,

Figure 1 is a small-scale diagrammatic side elevation of a railway car;

Figure 2 is on the left-hand side a small-scale diagrammatic end elevation of the lower part of the railway car;

Figure 3 is a fragmentary perspective and section along line 3—3 of Figure 1 on a larger scale showing the connection between the floor structure, the center sill, one side wall, and one of the cross bearers;

Figure 4 is a fragmentary section along line 4—4 of Figure 1 showing on a larger scale one side margin of the underframe and the adjoining lower marginal portion of one side wall;

Figure 5 is a section along lines 5—5 of Figures 1 and 6 corresponding to Figure 4 showing the

2

end of one of the bolster beams and its connection to side sill and side wall;

Figure 6 is a fragmentary section and inside elevation along line 6—6 of Figure 5 showing the bolster beam and the adjoining floor panels in section and the underframe side sill and adjoining side wall parts in inside elevation;

Figure 7 is a section in the plane of the rectangle shown by dot-and-dash line 6 in Figure 3;

10 Figure 8 is a fragmentary section corresponding to Figure 4, taken along line 8—8 of Figure 9 at the location of one of the door openings and showing the formation of a step as reinforcing hollow sill structure; and

15 Figure 9 is a fragmentary outside elevation on a larger scale of the region surrounded in Figure 1 by dot-and-dash line 9.

The railway car illustrated in the drawing has an underframe U, side walls S, a roof R, and end walls E.

20 The underframe U comprises an end sill 10 at and a bolster beam 11 near each end, an end center sill member (not shown) interconnecting each end sill and bolster beam, and a sheet metal channel section center sill 12 inboard of and between the bolster beams. Secured to the top of the center sill 12 and of the end center sill members are shear panels comprising sheets 13 reinforced at longitudinally spaced intervals by 25 upstanding profiles 14. The outer ends of the panels 13 and profiles 14 fit telescopingly between the upper walls 15 and the lower walls 16 of inwardly facing channel sections 17, each having a generally vertically arranged bottom wall 18. The sections 17 form underframe side sills and 30 extend on both sides of the underframe uninterrupted over the length of the car. Only the bottom wall 16 is cut out at the location of the bolster beams, as will be pointed out later on.

35 The sections 17 form underframe side sills and extend on both sides of the underframe uninterrupted over the length of the car. Only the bottom wall 16 is cut out at the location of the bolster beams, as will be pointed out later on. The overlapping portions of the sheets 13 and the profiles 14 are connected, preferably by electric spot welding, with the walls 15 and 16 of the side sills 17 and the top flanges 19 of the center sill, as well as with corresponding flange portions of the end center sill members. See Figures 3, 4, and 5.

40 Each side wall S has vertical posts 20, 21 which are spaced from each other in the longitudinal direction of the car and which, after final assembly, project downwardly beyond the side sills 17 of the underframe. The lower portions of the posts 20, 21 are interconnected on their insides by a web 22 which constitutes part of the side wall structure and extends preferably without interruption over the entire length of the body. On the outside, the posts are structurally connected with another shear panel 23 which is longitudinally stiffened by corrugations 24 or

other appropriate stiffening members. The space between the inner web 22 and the outer panel 23 is closed by a U-section profile 25 overlappingly secured to the lower margins of the panel and the web and overlappingly secured to inside 5 and outside of the posts. See Figures 3, 4, 5, and 7.

The side walls are truss structures in which the inner and outer webs 22, 23 together with the U-section 25 constitute the lower chord in 10 the form of an upwardly facing deep and narrow U-section which is vertically stiffened at short intervals by the posts 21, 22. This construction affords great strength coupled with relatively light weight.

The connection between each side wall unit S and the underframe unit U can easily be made by securing the side wall web 22 in the region of overlap to the outside of the bottom wall 18 of the underframe sill 17. Such connection may be made over most of the length of the body by electric spot welding.

At certain intervals between the bolster beams 11, further cross bearers 26 are formed by the aforesaid floor panel with its profiles 14 and by an additional hat section profile 27. See Figures 3 and 7. This hat section is secured in the middle region by its bottom wall 28 to the underside of the center sill 12, whereas its upwardly and laterally projecting ends have the side walls 29 fit between and secured to two closely spaced webs 30 of the reinforcing profiles 14, as clearly shown in Figure 7. The webs 30 with the adjoining panel portions 13 and the member 27 together form a cross bearer of light weight embracing the center sill 12 at top and bottom. See Figure 3.

The bolster beam 11 is a closed box section having longitudinally spaced side walls 31, a bottom wall 32 and a top wall 33. While the bottom wall is substantially horizontally arranged, the top wall slopes downwardly toward its ends. All four walls of the bolster are connected at each end by a plate or end wall 34 which projects upwardly beyond the top wall 33 and is reinforced by triangular gussets 35 tied into the top and side walls. See Figures 5 and 6.

As mentioned hereinbefore, the side sills 17 of the underframe have their walls 16 cut away at the intersection with the bolsters. On this account, the upper wall 15 and the outer wall 18 of the side sills may be placed over the outside and upper margin of the bolster end wall 34 and connected therewith. Each side wall in its region of overlap with the bolster end wall is strongly reinforced by two closely spaced posts 20 and by brackets and gussets 36. The overlapping portions of side wall, underframe side sill and bolster end plate 34 are strongly interconnected by bolts or rivets 37.

The end corners of the side walls are reinforced by end posts 21 by which they are secured to the end sills 10. See Figures 1 and 2.

The side walls surround door openings 38 which, of course, means a substantial weakening of the side wall trusses. This weakening is, see Figures 1, 8, and 9, compensated for along the lower margin of a door opening by a step 39 forming a hollow or box sectional beam extending beyond the posts flanking such opening. The step for one opening comprises longitudinally spaced brackets 40 firmly secured in overlapping relation to the sides of the lower ends of some of the posts 20 and, especially beyond the door opening, to similar vertical frame members, in-

15 dicated at 20' in Figure 9, of the side wall so that the brackets 40 project outwardly beyond the posts and members 20, 20' in a region where the outer shear panel 23 is cut away. The top, the outer and the bottom margins of the brackets 40 are structurally connected with metal sheets 41 thereby forming a box sectional beam firmly tied into the posts and connected with the adjoining portions of the outer shear panel 23 and the bottom rail 25 of the side walls. The top sheet 41 may have an inner upwardly directed extension 42 which is overlappingly secured to the outside of the web 22 and to the adjoining posts 20 thereby affording additional reinforcement. The lower margin of the side wall is braced in the step region by member 43 diagonally interconnecting the lower margin of the side wall with the underside of the floor structure 13 (Figure 8).

20 In regard to the floor structure, it may still be mentioned that two sheets or panels 13 end on the sides of the bolster beam 11 where they have reinforcing profiles 14 firmly secured to the sides of the bolster. See Figures 5 and 6.

25 The described construction is preferably made throughout of high-tensile sheet metal, preferably of cold-worked austenitic stainless steel, with the exception of the end underframe members, including end sill 10 and bolster beam 11. The sheet metal members are preferably connected throughout by overlap spot weld joints as indicated throughout the drawing in conventional manner by small crosses and by black dots, respectively. The entire body, composed of side walls, underframe, roof, and end walls, represents a hollow section beam transmitting all stresses and carrying all weight.

30 One advantage of the construction is also that it permits the door opening to extend downwardly beyond the side sills without cutting into the latter. Such extended door opening affords also maximum toe room on the entrance step.

35 Certain features disclosed in this application form the subject matter of the inventor's applications Cover Panel for Vehicles, Especially 45 Railway Cars, Serial No. 782,001, and End Underframe for Railway Cars, Serial No. 782,000; and of the application Reinforced Shear Web, Especially 50 for Underframes of Railway Cars and Similar Vehicles, of the inventor and Walter B. Dean, Serial No. 782,003, now abandoned, all filed simultaneously with the present application on October 24, 1947.

55 While one embodiment of the invention is shown and described, it should be understood that the invention is susceptible to many modifications which will easily occur to those skilled in the art, and that, therefore, protection is sought for the invention as covered by the spirit 60 and the language of the attached claims.

What is claimed is:

1. Side wall for railway cars in which the side walls project downwardly beyond the underframe structure, said side wall comprising as a pre-65 assembled unit a plurality of longitudinally spaced vertical posts interconnected on the inside as well as on the outside by shear panels, both said panels extending downwardly to the lower ends of the posts, said panel on the inside extending to and terminating near the top surface of the underframe structure and said panel on the outside extending upwardly beyond said panel on the inside, said shear panels constituting a lower chord structure and the inner 70 panel by its upper marginal region forming con-

necting means between the side wall unit and the adjoining margin of the underframe structure.

2. Side wall truss for railway cars comprising a plurality of longitudinally spaced vertical posts having their lower end portions interconnected on the inside as well as on the outside by shear panels, both said panels extending downwardly to the extreme lower ends of the posts, said panel on the inside extending to and terminating near the top surface of an adjoining underframe structure while said panel on the outside extends further up, the space between the lower margins of said shear panels being closed by a longitudinal member made separately from said panels, said shear panels and said member constituting a lower chord structure and the inner panel forming connecting means between the side wall and an adjoining underframe structure.

3. In a railway car comprising side wall units and an underframe unit connected with each other in final assembly, said underframe unit having channel section side sills facing toward the middle of the car and telescoping over the ends of transverse members interconnecting the side sills, each side wall unit comprising longitudinally spaced vertical posts interconnected at least on the inside by a longitudinally extending vertical shear web, the shear web of each side wall overlapping the outside of the bottom wall of one of the underframe side sills, said underframe unit and said side wall units being connected with each other in the regions of overlap of the said shear webs and said bottom walls of the side sills.

4. In a side wall for vehicles, a plurality of longitudinally spaced vertical posts and reinforcing members, brackets secured to at least some of the posts and members, said brackets projecting outwardly beyond the side wall, longitudinally extending metal sheeting bridging the space between and structurally secured to said brackets, the brackets and the sheeting forming a step and simultaneously a box section beam reinforcing the side wall structure, said step extending over at least part of the length of said side wall.

5. In a side wall for vehicles, a door opening, vertical door posts on both sides of said opening, brackets secured to said posts and extending outwardly beyond the side wall, said brackets having their outwardly projecting margins covered by and structurally secured to metal sheeting which closes the space between successive brackets and presents a step and simultaneously a box section girder reinforcing the side wall structure where it is weakened by the door opening.

6. In a side wall according to claim 5, having a vertical frame member located in longitudinal direction at a short distance beyond the opening, a further bracket secured to said frame member, said sheeting extending and being secured to said further bracket so as to extend the girder formed by the step beyond the opening and distribute stresses into portions of the side wall adjoining the opening.

7. In a vehicle underframe comprising side sills, a center sill and a shear panel reinforced by transverse vertical webs, said panel being secured to the top of the center sill and having its ends connected with the side sills, certain of said webs being closely spaced from each other in longitudinal direction, a hollow-section chord structure extending across and secured to the underside of the center sill and having two longitudinally spaced walls at its ends fitted between

and secured to said closely spaced webs thereby forming with such webs an effective cross bearer embracing the top and bottom of the center sill.

8. In a vehicle underframe comprising side sills, a center sill and a shear panel reinforced by transverse vertical webs, said panel being secured to the top of the center sill and having its ends connected with the side sills, certain of said webs being closely spaced from each other in longitudinal direction, a chord structure of inverted channel section extending across and being secured by its bottom wall to the underside of the center sill and having its side walls at its ends fitted between and secured to said closely spaced webs thereby forming with such webs and the adjoining portions of the shear panel an effective cross bearer embracing the center sill from top and bottom.

9. In a side wall for vehicles of elongated prismatic shape, such as railway cars, said side wall comprising rigidly inter-connected longitudinal and upright structural members so as to form a main load-sustaining and stress-transmitting element of the vehicle, brackets stress-transmittingly secured to the side wall near its lower margin and projecting outwardly beyond the outer surface of the side wall, said brackets being spaced from each other in the longitudinal direction of the wall, longitudinally extending metal sheeting bridging the space between and structurally secured to the outwardly projecting surfaces of said brackets, the brackets and the sheeting forming a step and simultaneously a hollow-section beam reinforcing the side wall structure, said step extending at least over part of the length of the side wall.

10. In a side wall for vehicles, a plurality of longitudinally spaced vertical posts and reinforcing members, longitudinally extending webs structurally secured to the lower ends of said posts and members and forming a lower chord structure of the side wall, brackets structurally secured to at least some of the posts and members, said brackets extending outwardly beyond the side wall, longitudinally extending metal sheeting bridging the space between and structurally secured to the outwardly projecting margins of said brackets, the longitudinal margins of said sheeting being secured to said webs, the brackets and the sheeting forming a step and simultaneously with said webs a closed box section beam reinforcing the side wall structure, said step extending over at least a part of the length of the vehicle.
